REFLECTOR BUTTON MOUNT

Harry R. Johnson, Baltimore, Ohio

Application May 21, 1936, Serial No. 81,108

1 Claim. (Cl. 88—82)

This invention appertains to new and useful improvements in means for mounting reflector buttons such as are worn by motorcyclists on their belts.

The principal object of the present invention is to provide a reflector button mount which will yield the greatest amount of reflection and be exceedingly attractive when worn.

During the course of the following specification, other important objects and advantages of the invention will become apparent to the reader.

In the drawing:

Figure 1 represents a fragmentary front elevational view of a disk-shaped button carrier with buttons installed thereon;

Figure 2 is a vertical sectional view through the construction shown in Figure 1;

Figure 3 is a fragmentary front elevational view of a belt provided with a button mount;

Figure 4 is a section on line 4—4 of Figure 3.

Referring to the drawing wherein like numerals designate like parts, it can be seen in Figures 1 and 2 that the button carrier consists of a disk-shaped back wall 5 and a similarly shaped front wall 6. The back wall 5 has a clip 7 of spring material whereby the assembly can be fastened to the belt of the wearer.

The button mount consists of a cup-shaped member 8 of outwardly narrowing construction which at its inner end is provided with a lateral flange 9 adapted to be overlapped by the front wall 6 at the edge portions of the opening through which the said cup members 8 extend. These flanges 9 rest against the back wall 5 and the glass reflecting buttons 10 are located in the cup members 8 and are provided with reduced bead-like extensions 11 protruding through openings

in the front ends of the cups 8 as shown in Figure 2.

The belt construction shown in Figure 3 consists of the back wall 12 and the front wall 13 with the longitudinal edge portion of the back wall 12 disposed over and secured to the front side of the front wall 13, as shown in Figure 4. Interposed between these walls 12—13 is the belt strip 14 against which the flanged end portions 9^a of the cup-shaped structures 8^a abut. These cup-shaped structures 8^a protrude through openings in the front wall 13 and each has an opening at its forward end through which the button-like extension 11^a of the encompassed last button 10^a protrudes.

While the foregoing specification sets forth the invention in specific terms, it is to be understood that numerous changes in the shape, size, and materials may be resorted to without departing from the spirit and scope of the invention as claimed hereinafter.

Having described the invention, what is claimed as new is:

A reflecting button mount comprising a back wall, a front wall, one of said walls being lapped over the edge portion of the other wall for holding said walls in definite spaced relation, said front wall having an opening therein, a tapered cup-shaped structure having a flange at its large end, said flange being interposed between the front wall and the rear wall with the cup-shaped structure protruding through the opening in the front wall, a reflecting button mounted in the said cup-like structure, and a resilient strip snugly interposed between the said flange and the back wall.

HARRY R. JOHNSON.
